OVEN OBSERVATION WINDOW
CONSTRUCTION

John F. Hennessy, Rockford, Ill., assignor to Geo.
D. Roper Corporation, Rockford, Ill., a corporation of Illinois

Application July 18, 1940, Serial No. 346,122

13 Claims. (CL 126—200)

This invention relates to improvements in observation windows for ranges, and more particularly for oven doors of cooking ranges.

In providing an observation window for an oven door, it has been found that the heat insulating efficiency of such a window is vastly improved through the provision of two dead air spaces instead of only the one usually provided. As this requires a third glass panel spaced between outer and inner panels, the problem is presented of providing satisfactory mounting means which are relatively concealed for this intermediate panel while utilizing ordinary and inexpensive sheet metal construction throughout. It is, therefore, the principal object of my invention to provide an improved sheet metal door construction for supporting the three panels in spaced parallel relationship in the window opening so that no unsightly mounting devices are visible when looking through the window into the oven and no fastenings are exposed on the outside of the door.

Another object of my invention is to provide sheet metal means for mounting the three glass panels of the observation window so constructed and arranged that no strains apt to cause cracking of one or more of the panels are imposed thereon despite the otherwise relatively rigid construction of the door.

Another problem encountered with observation windows for ranges is providing one that may be easily cleaned. Moisture often collects upon the unexposed faces of the glass panels during the preheating stage, and, if dirt or grease happens to be present in the dead air spaces between the glasses, they will eventually become clouded and, consequently, defeat the very purpose for which they are provided. The provision of three glass panes further complicates this cleaning problem. It is, therefore, another object of my invention to provide means for mounting the glass panels so that two of them may be easily removed for cleaning, permitting the third to be cleaned without removal from the range door.

The invention is hereinafter described by reference to the accompanying drawings, wherein—

Fig. 1 is a perspective view of a portion of a cooking range showing an oven door provided with an observation window made in accordance with my invention;

Fig. 2 is a perspective view of the oven door looking at the inner side;

Fig. 3 is a vertical section on the line 3—3 of Fig. 2;

Fig. 4 is a vertical sectional detail of one of the bottom corners of the inner glass panel show-

ing the cotter pin means for securing this glass panel to the inner door panel;

Fig. 5 is a vertical sectional detail of one of the bottom corners of the middle glass panel showing the corner slot and one of the panel abutting eyebrows used in securing this panel in position in the sheet metal spacer frame;

Fig. 6 is a horizontal sectional detail on the line 6—6 of Fig. 3, showing how the upper inner edge portion of the spacer frame is connected to the inner door panel;

Fig. 7 shows the glass and sheet metal parts of the oven door window in exploded relation, and

Fig. 8 is a view of a portion of the inner door panel taken on the line 8—8 of Fig. 7.

The same reference numerals are applied to corresponding parts throughout the views.

Referring to the drawings, a rectangular sheet metal panel 9 having a rectangular opening 11 defined by an inwardly extending flange 12 forms the front or outer panel of the oven door 13 of the range 14. An inner door panel 15 also of rectangular form and having a similar opening 16 defined by an inwardly extending flange 17 is stamped to the dished form indicated at 18 in Fig. 2 for proper spacing of the window portions of the inner and outer door panels.

A rectangular molded glass panel 19 of a high heat resisting material such as "Pyrex" and having a peripheral shoulder portion 21 closes the opening 11 in the outer door panel 9 and has abutment with the flange 12 by its shoulder portion, placing the outer faces of the sheet metal panel 9 and glass panel 19 in a nearly flush relationship.

A rectangular sheet metal spacer frame 22 has its forward marginal edge portion bent radially outwardly and forwardly on all four sides of the frame, as indicated at 23, to provide a rabbet portion for engagement with the inner side and peripheral edge of the glass panel 19 to secure the glass panel 19 within the panel 9 and at the same time support the spacer frame 22 in proper relation to the panels 9 and 19.

At its inner edges, the spacer frame 22 has on each of its four sides an outwardly extending flange 24 and the top one of these flanges is slotted, as at 25, to receive correspondingly located lugs 26 on the edge of the inner sheet metal panel flange 17. The other flanges 24 merely abut the edge of flange 17. As will be further described, it is apparent that the spacer 22 is held in a floating relationship to the outer and inner door panels 9 and 16 inasmuch as it directly engages one of the said panels at one portion

only, namely, where the lugs 26 enter the slots 25. In particular, the positioning of the spacer 22 at its front edges by the glass panel 19 permits expansion of the glass 19 through heat without imposing stresses thereon apt to cause immediate or eventual cracking.

A duplicate rectangular glass panel 27, interchangeable with panel 19 and having a peripheral shoulder portion 28 seats within a frame formed by the flange 17 of panel 15 and the rear flange 24 of the spacer 22. The glass panel 27 is secured within this channel at its bottom edge by the insertion of cotter pins 29 which are disposed diagonally across opposite bottom corners of panel 27 and entered through holes 31 in the bottom corners defined by the flange 17, as shown in Fig. 4.

A middle glass panel 32 dividing the space between the front and rear glass panels 19 and 27 into two dead-air, insulating compartments 33 and 34 is of plate glass since it has been found that it is not subjected to the uneven heat shocks which are apt to cause cracking. As has been mentioned, the other glass panels 19 and 27 are of "Pyrex" or comparable material in order to resist breakage due to the uneven heating to which they are subjected. The glass panel 32 seats within the spacer frame 22, its lower edge portion abutting radially inwardly struck spaced eyebrows 35 provided on the bottom portion of the spacer 22. The bottom portion of the glass panel 32 engages at its corners 36 in slots 37 provided in the lower corners of the spacer 22, as shown in Fig. 5.

The top portions of the glass panels 27 and 32 are held in spaced relation and secured to the door by means of an S-shaped clip 38 and a clamp 39. The clip 38 has one of its U-bends fitting over the top edge of the glass panel 27 while its other U-bend 41 abuts the inner side of glass panel 32 to space the said panels and hold the upper portion of panel 32 in engagement with its locating eyebrows 35 on the upper portion of the spacer 22. The clamp 39 secures the clip 38 and related glass panels in place when it is fastened to the inner door panel 15. The clamp 42 abuts the clip 38, as shown in Fig. 3. A screw 43 entered in a threaded hole provided in an inverted U-shaped clip 44 positioned in a slot 45 in the inner panel 15 secures the clamp 39 to the panel 15, as clearly appears in Fig. 3.

It is apparent that expansion through heating of the glass panels 27 and 32 will not cause breakage because of the capacity of the flange 17 of panel 15 to yield under such stress and generally shift independently of spacer 22. The outer panel 19 is not subjected to much heat but is also free to expand because of the yieldable flanges 12 and 23 so that there is no danger of cracking.

It is evident that all that is required in cleaning the glass panels 27, 32, and 19 is the removal of the clamp 39, upon removal of a single screw 43. This permits panels 27 and 32 to be removed upon disengagement of their bottom corners from the pins 29 and slots 37, respectively. Such removal obviously makes the inner side of panel 19 accessible for cleaning. To replace the panels 27 and 32, the operator merely reinserts their bottom corners in their proper places and seats their edges in abutment with flanges 24 and eyebrows 35, respectively, and replaces the clamp 39 and screw 43, being careful to replace the clip 38 on the middle of the top portion of panel 27 before the latter is put in place.

It is believed the foregoing description conveys

a good understanding of the objects and advantages of my invention. The appended claims have been drawn with a view to covering all legitimate modifications and adaptations.

5 I claim:

1. A structure of the character described comprising, in combination, a unitary body member formed by an inner or rear sheet metal panel having an opening defined by a forwardly extending flange, and an outer or front sheet metal panel having an opening defined by a rearwardly extending flange, a separate unitary spacer frame located between the said front and rear panels and adapted to be assembled in said body through the opening in one of said panels, the said spacer frame having an outwardly extending peripheral flange on its rear edge and a rabbet portion formed on its front edge, a front glass pane having a shouldered peripheral edge portion, the said pane being positioned within the rabbeted edge of said spacer frame with its shoulder disposed in engagement with the edge of the rearwardly extending flange of the front panel, a rear glass pane fitting within the forwardly extending flange of said rear panel in abutment with the outwardly extending flange on the rear edge of the spacer frame, means for holding said rear pane in place in the rear panel at two of its adjacent corners, a demountable clamp bearing against a diametrically opposite edge of said pane, and means for detachably securing said clamp on said rear panel.

2. A structure of the character described comprising, in combination, a unitary body member formed by an inner or rear sheet metal panel having an opening defined by a forwardly extending flange, and an outer or front sheet metal panel having an opening defined by a rearwardly extending flange, a separate unitary spacer frame located between the said front and rear panels and adapted to be assembled in said body through the opening in one of said panels, the said spacer frame having an outwardly extending peripheral flange on its rear edge and a rabbet portion formed on its front edge, a front glass pane having a shouldered peripheral edge portion, the said pane being positioned within the rabbeted edge of said spacer frame with its shoulder disposed in engagement with the edge of the rearwardly extending flange of the front panel, a rear glass pane fitting within the forwardly extending flange of said rear panel in abutment with the outwardly extending flange on the rear edge of the spacer frame, and means for detachably securing the rear pane in place in the rear panel.

3. A structure of the character described comprising, in combination, an inner or rear sheet metal panel having an opening defined by a forwardly extending flange, an outer or front sheet metal panel having an opening defined by a rearwardly extending flange, a spacer frame located between the said front and rear panels, the said spacer frame having an outwardly extending peripheral flange on its rear edge and a rabbet portion formed on its front edge, a front glass pane having a shouldered peripheral edge portion, the said pane being positioned within the rabbeted edge of said spacer frame with its shoulder disposed in engagement with the edge of the rearwardly extending flange of the front panel, an intermediate glass pane and a rear glass pane, the intermediate glass pane fitting within the spacer frame in spaced relation to the front and rear glass panes, means for holding said intermediate glass pane in the position stated, the rear

glass pane fitting within the forwardly extending flange of said rear panel in abutment with the outwardly extending flange on the rear edge of the spacer frame, and means for detachably securing the rear glass pane in place in the rear panel.

4. A structure of the character described comprising, in combination, an inner or rear sheet metal panel having an opening defined by a forwardly extending flange, an outer or front sheet metal panel having an opening defined by a rearwardly extending flange, a spacer frame located between the said front and rear panels, the said spacer frame having an outwardly extending peripheral flange on its rear edge and a rabbet portion formed on its front edge, a front glass pane having a shouldered peripheral edge portion, the said pane being positioned within the rabbeted edge of said spacer frame with its shoulder disposed in engagement with the edge of the rearwardly extending flange of the front panel, an intermediate glass pane and a rear glass pane, the intermediate glass pane fitting within the spacer frame in spaced relation to the front and rear glass panes, means on said spacer frame for detachable interlocking engagement with one end of the intermediate glass pane to hold it in the position stated, said rear glass pane fitting within the forwardly extending flange of said rear panel in abutment with the outwardly extending flange on the rear edge of the spacer frame, means on the rear panel for detachable interlocking engagement therein of one end of the rear glass pane to hold it in the position stated, both last named panes having the same end so held, the opposite end of each of said panes being free from such interlocking engagement, spacing means holding the free ends of said intermediate and rear glass panes in spaced relation, and means for detachably securing the free end of the rear glass pane in place in the rear panel.

5. A structure of the character described comprising, in combination, a unitary body member formed by an outer panel having an opening provided therein and an inner panel having a registering opening provided therein, the opening in the outer panel being smaller than that in the inner panel but being substantially in centered relation thereto, an outer glass pane on the inner side of the outer panel having supporting means projecting outwardly into the opening therein, a separate unitary spacing frame between the panels adapted to be assembled in said body through the larger opening in the inner panel, said frame having one end portion engaging the outer glass pane and located and supported thereby, said frame having the other end portion defining a marginal abutment in the larger opening in the inner panel, an inner glass pane fitting in the opening in the inner panel against said abutment to hold the spacer frame in place between the panels and against the outer glass pane, means for detachably securing the inner glass pane in place in the opening in the inner panel, and interfitting means on the inner end of the spacer frame and inner panel for supporting the spacer frame in assembled relation to the inner panel when the inner glass pane is removed.

6. A structure of the character described comprising, in combination, a unitary body member formed by an outer panel having an opening provided therein and an inner panel having a registering opening provided therein, the opening in the outer panel being smaller than that in the

inner panel but being substantially in centered relation thereto, an outer glass pane on the inner side of the outer panel having a portion projecting outwardly into and closing the opening therein, a spacing frame between the panels having one end portion fitting over the periphery of the outer glass pane and located and supported thereby, said frame having the other end portion defining a marginal abutment in the opening in the inner panel, an inner glass pane fitting in the opening in the inner panel against said abutment to hold the spacer frame in place between the panels and against the outer glass pane, means for detachably securing the inner glass pane in place in the opening in the inner panel, an intermediate glass pane disposed between and in spaced substantially parallel relation to the outer and inner glass panes and fitting in the spacer frame, and means for detachably securing said intermediate glass pane in such position.

7. A structure of the character described comprising, in combination, a unitary body member formed by an outer panel having an opening provided therein and an inner panel having a registering opening provided therein, the opening in the outer panel being smaller than that in the inner panel but being substantially in centered relation thereto, an outer glass pane on the inner side of the outer panel having a portion projecting outwardly into and closing the opening therein, a spacing frame between the panels having one end portion fitting over the periphery of the outer glass pane and located and supported thereby, said frame having the other end portion defining a marginal abutment in the opening in the inner panel, an inner glass pane fitting in the opening in the inner panel against said abutment to hold the spacer frame in place between the panels and against the outer glass pane, means for detachably securing the inner glass pane in place in the opening in the inner panel, an intermediate glass pane disposed between and in spaced substantially parallel relation to the outer and inner glass panes and fitting in the spacer frame, means on the spacer frame for detachable interlocking engagement of one end of the intermediate glass pane therein to hold said pane in place between the outer and inner panes, the other end of said intermediate glass pane being free, means in the spacer frame providing an abutment for engagement with that side of the free end of said intermediate glass pane remote from the inner glass pane, and spacing means between the inner glass pane and the free end of the intermediate glass pane for holding the panes spaced apart and with the free end of the intermediate pane in engagement with the abutment therefor.

8. A structure of the character described comprising, in combination, a unitary body member formed by an outer panel having an opening provided therein and an inner panel having a registering opening provided therein, the opening in the outer panel being smaller than that in the inner panel but being substantially in centered relation thereto, an outer glass pane on the inner side of the outer panel having a portion projecting outwardly into and closing the opening therein, a spacing frame between the panels having one end portion fitting over the periphery of the outer glass pane and located and supported thereby, said frame having the other end portion defining a marginal abutment in the opening in the inner panel, an inner glass pane fitting in the opening in the inner panel against said abutment

to hold the spacer frame in place between the panels and against the outer glass pane, an intermediate glass pane disposed between and in spaced substantially parallel relation to the outer and inner glass panes and fitting in the spacer frame, one end of the intermediate glass pane being detachably fixedly supported in the frame to hold said pane in place between the outer and inner panes, the other end of said intermediate glass pane being free, means in the spacer frame providing an abutment for engagement with that side of the free end of said intermediate glass pane remote from the inner glass pane, spacing means between the inner glass pane and the free end of the intermediate glass pane for holding the panes spaced apart and with the free end of the intermediate pane in engagement with the abutment therefor, and means for detachably securing the inner pane in place in the inner panel comprising means on the inner panel for detachable interlocking engagement of the same end of the inner glass pane as the intermediate glass pane has detachably interlocked with the spacer frame, whereby both of said panes have the same ends free, and means for detachably securing the free end of the inner pane in place in the inner panel.

9. A structure of the character described comprising, in combination, a unitary body member formed by sheet metal inner and outer walls in spaced substantially parallel relation both having openings provided therein, the openings being substantially in centered relationship to one another and both being defined by marginal flanges bent inwardly from the walls toward one another, the flanges being yieldable radially in relation to the openings to an extent sufficient to eliminate danger of cracking of glass panes set in the openings in engagement with the flanges, two spaced substantially parallel glass panes set in said openings in engagement with said flanges, means retaining the first of said panes against outward displacement from its opening, a separate unitary sheet metal spacer frame adapted to be assembled in said body through the opening in one of said walls, said frame having means at one end for abutment with the inner side of said first pane to hold the pane against inward displacement from the opening, said frame also having

means for preventing radial displacement of the frame relative to said first pane, said frame being smaller in dimensions than the opening in the other wall but disposed in substantially centered relation thereto, the second pane in the last-mentioned opening having abutment with the adjacent end of the spacer frame whereby said second pane is held against inward displacement while serving to hold said spacer frame in assembled relation to the first pane, and means for preventing outward displacement of the second pane from the opening in the last-named wall.

10. A structure as set forth in claim 9, including an intermediate glass pane disposed between and in spaced substantially parallel relation to the other two panes, and means for detachably securing said pane in place in the spacer frame.

11. A structure as set forth in claim 9, including an intermediate glass pane disposed between and in spaced substantially parallel relation to the other two panes, and means for detachably securing said pane in place in the spacer frame in a position closer to the pane that is subjected to the most heating in service.

12. An oven door having spaced inner and outer walls with registering openings provided therein, inner and outer glass panes closing said openings in spaced substantially parallel relation to one another, and a third intermediate glass pane supported in spaced substantially parallel relation to the inner and outer panes but close to the inner pane.

13. An oven door having spaced inner and outer walls with registering openings provided therein, an outer glass pane for the opening in the outer wall, a sheet metal spacer frame between said walls holding said outer pane in assembled position, an inner glass pane for the opening in the inner wall positioned in said opening by abutment with the spacer frame, means for detachably securing said inner pane, an intermediate glass pane supported in said spacer frame in spaced substantially parallel relation to the inner and outer panes but close to the inner pane, and means for detachably securing said intermediate pane in the position stated.

JOHN F. HENNESSY.
